DEVICE FOR LIFTING BRICKS AND
THE LIKE

Alba H. Rice, Mansfield, Ohio

Application August 17, 1945, Serial No. 610,902

16 Claims. (Cl. 294—63)

1

This invention relates to a device in the nature of a grab or a pair of tongs for lifting a stack of brick or similar material as a unit. It is of the type wherein there is a pair of jaws having means to engage opposite sides of the bottom layer of the stack of brick or similar material, the jaws being carried by means adapted to be suspended from a cable and the cable operating to force the jaws tightly against opposite sides of the stack of material as the cable starts to lift the device.

The general object of the invention is to provide a machine of the type mentioned while having ample strength for the stresses encountered shall be comparatively light and simple in construction and inexpensive in manufacture. Another object is to provide in the device manually operated means for effectively clamping the jaws against opposite sides of the stack preliminary to the action of the lifting cable. A further object is to provide simple means actuated by the lifting cable to tighten the grip of the jaws on the load. Still another object is to provide means for maintaining the jaws in their separated or idle condition notwithstanding lifting or lowering of the device by the cable to position it.

A preferred embodiment of the machine is illustrated in the drawings hereof and is hereinafter more fully described, and the essential novel features are set out in the claims.

In the drawings, Fig. 1 is an end elevation of my lifting device in the open position ready for application to a stack of bricks indicated in broken lines, the lifting portion of the device being abnormally spread apart in this view for clearness of illustration; Fig. 2 is an end elevation showing the device after the manual clamps have been operated to clamp the jaws against the stack of bricks and the lifting power applied; Fig. 3 is a side elevation (partly broken away) of the device in the condition of Fig. 2; Fig. 4 is a separated perspective of different members of the tightening mechanism operated by the lifting cable; Fig. 5 is a transverse section along the axis of the tightening device, as indicated by either of the lines designated 5 on Fig. 3; Fig. 6 is an approximately horizontal cross-section to the manual clamping device, the plane of the section being indicated by the line 6—6 on Fig. 2.

My device provides a pair of clamping jaws adapted to be lifted by means at their upper ends and provided with means at their lower ends to engage the lower layer of a pile of bricks.

2

Each jaw comprises a base bar 10 adapted to extend horizontally and bear against opposite faces of the brick stack (indicated at A), a pair of upright jaw bars 11 or 12 extending upwardly from the base bar, and a top bar 13 parallel with the base bar and secured to the jaw bars near their upper ends, these top bars being shown as flanged and bolted in place.

Each jaw bar is formed at its upper end with an eye 14 loosely surrounding a supporting shaft 20, as hereinafter explained. As shown in the drawings, the eyes are made by clips doubled on themselves, their arms 15 being secured to opposite sides of the jaw bar 11 or 12.

15 Mounted on each shaft 20 between the two eyes 14 of the jaws is a spreading device operated by the lifting cable adapted to spread the upper ends of the jaws apart. This action forces the lower ends inwardly by reason of intermediate 20 tying connection located above the stack of bricks to be lifted and between the jaws.

As shown the spreading device comprises a central rotary cam 21 of the shaft and a pair of opposed seating members 22 also surrounding 25 the shaft. Each seating member has rigidly connected to it, an angle bracket 23 which extends downwardly and then outwardly as of 24. The outward portion is bifurcated and straddles the upper end of the corresponding jaw bar. This prevents the seating member 22 from rotating, while it is free to move outwardly by operation of the central member 21. Outside of the eye of each jaw there is mounted on the shaft a helical compression spring 25, shown as compressed between a washer 26 resting against the eye and a suitable abutment (illustrated by a washer and cotter pin 27) on the end portion of the shaft. These springs, therefore, tend to keep the eyes in contact with the brackets 23.

40 The central cam member 21 and each of the seating members 22 are of the form shown in Fig. 4. Each member 22 has a flat outer face while its inner face is composed of two helical surfaces 28 each extending for half a circle thus leaving an abrupt radial plane 29 diametric of the member separating the two helical surfaces. Similarly, the movable cam member 21 has its opposite faces formed with two spiral semi-circular faces 30 increasing in the same circular direction and separated by diametric plane 31.

45 Each of the double spaced central blocks 21 is provided with a rigid operating arm 32 extending toward the center of the machine. For convenience of construction, the double-faced cam block 21 may conveniently be made of two parts

with flat adjacent faces as shown in Fig. 5, and the arm 32 may be a plate extending between these faces and about the shaft 20, the two members 21 being then bolted together through the arm as indicated at 33 in Fig. 5.

The two cam-operating arms are spaced apart at their inner ends as shown on Fig. 3 and each arm is connected by a link 34 to a cross head 35 to which the hook B of a lifting cable may be attached. It results from this construction that the upward pull on the cable swings the arms 32 upwardly and causes the cam block 21 to spread to blocks 22, the effect of which will be hereinafter explained. The cams are normally maintained in their idle position by springs 36 attached thereto and to a suitable anchorage below the eyes. I find it convenient to use as the anchorage a suitable bar 75 which is provided for another purpose as hereinafter explained.

Secured to the jaw bars 12 on one side adjacent the region where the jaw bar bends (which is higher than the top of the stack of bricks to be lifted), are suitable clips 50, each shown as comprising a doubled strip of metal embracing the jaw bar and extending inwardly therefrom. This clip is shown as clamped on the jaw bar by a screw 51 which also holds a threaded rod 52 having an eye lying between the two portions of the clip.

Secured to the other jaw bars 11, in the corresponding location, are outwardly extending brackets 60. Pivot to each bracket is a manual lever 61, the pivot being indicated at 62. The manual lever 61 is also pivoted to an inwardly and outwardly movable link 65, the pivot to the link being indicated at 66. To the inner end of the link 65 is secured a threaded rod 67. A turn-buckle yoke 68 connects the two rods 52 and 67, one of which has a right hand thread and the other a left hand thread.

It follows from the construction described that when the manual lever 61 is turned upwardly as shown in Fig. 1 its movable connection 62 with the jaw bar is carried outwardly of the pivotal connection 66 to the turn-buckle link 65 which acts as a strut, and thus the lower ends of the jaws are spread apart, swinging outwardly about their upper ends as a center. This is the position shown in Fig. 1, which position leaves the device ready to be lowered over a supply of brick to be lifted and to be caused to engage thereafter the bottom-most layer of the brick.

To cause the engagement with the load to be lifted, the manual clamping levers 61 are turned downwardly from the position of Fig. 1 to that of Fig. 2. This carries the pivots 66 of the jaw bars to the outside and clamps the lower ends of the bars 10 against the bottom layer of brick. Each bar 10 preferably has a facing 69 of rubber or other yielding material to enable a non-slipping engagement with the brick. It will be seen that the operation of the two manual levers causes an effective preliminary clamping of the lifting device to the load.

Now when a lifting stress is applied to the cable hook B the cam arms 32 are swung upwardly about the axes of the shafts 20 and the cam blocks 21 spread the cam blocks 22, forcing the upper ends of the jaws outwardly and compressing their springs. This action puts stress on the turn-buckle tie connection and tends to swing the lower end of the jaw bars inwardly, thus effecting a tightening of the clamping action. This augments the manual clamping ef-

fected by the hand levers 61 and clamps the lead so tightly that the entire stack of bricks may be readily lifted as a unit.

If desired, each of the brackets 60 secured to the jaw bars 11 may be a strip of sheet material doubled on itself about the jaw bar, as indicated in Fig. 6. The arm 61 may also be a doubled sheet metal member, as shown in that view, and likewise the link 65 may comprise two bars side by side. In such case the two bars may be secured by rivets 66 to the corresponding arms of the doubled hand lever 61, while these hand lever arms may be pivoted to the bracket 60 by a single through rivet 62, all as shown in Fig. 6. This is illustrative of a simple means of providing the bracket, link and lever in a light and economical form, but if desired the parts may be made in other manner and members of single thickness provided in place of doubled arms, as will be readily understood.

It is desirable that means be provided whereby the lifting cable attached to the hook B may lift the device without swinging the jaws inwardly, to enable it to be positioned with its jaws spread on opposite sides of the load. To effect this, I provide a pair of brackets 70 each pivoted at 71 to one of the jaw bars 12 and having a pin and slot connection at 72 with the other jaw bar 11. Mounted in the two brackets 70 is a rotatable rod 75 carrying a pair of hooks 76 each adapted to hook into an eye or opening 38 on the lower end of the linking links 34. When the hooks occupy these links in their lowermost position the links may not be moved relative to the jaws and, hence, the cam spreading mechanism is ineffective and the lifting cable may lift the whole device without causing the jaws to approach each other.

To make the application of the restraining hooks 76 automatic, I provide a pair of links 77 each connecting a rock arm 78 on a bar 75 with the corresponding manual lever 61. When the levers are turned up to idle position to spread the jaws, the hooks are swung into engagement with the link eyes 38, as shown in Fig. 1, and in this condition the lifting hook B may lift the whole device without changing the approach of the jaws. When, however, the levers 61 are thrown down to effect clamping of the pile of brick as shown in Fig. 2, this automatically swings 50 the restraining hooks 76 out from the lifting links, so that the upward movement of the lift hook B swings the cam arms and spread the upper ends of the jaws to force the lower ends into tightened position.

It will be understood from the description given that my lifting device is comparatively light and readily transported from place to place as desired by an attached cable-hook B. When the device is supported idle, the hooks 76, in the cam operating links maintain the jaws spread apart at their lower ends, so that the device may be readily lowered by the supporting cable in position with reference in an interposed pile of brick or material to be lifted.

When the device is in position it is merely necessary for the operator to adjust the turn-buckles, if necessary, and to force downwardly the two manual levers controlling the manual clamping. This brings the jaw blocks tightly 70 into an engagement with the lower end of the lower layer of brick and the device is ready for raising, the same movement freeing the restraining hooks from the cam arms. As soon as an upward pull is applied to the lifting hook B it 75 raises the cam arms more or less and spreads the

cams as to take up any slack and provides a tight clamping of the jaws against the brick.

The turn-buckles allow an adjustment of the jaws with reference to each other for different widths of stack to be lifted, and the yielding facing on the inner sides of the bars 10, allow some leeway in the clamping. The result is that the device may be very readily adjusted for the particular pile of brick to be lifted and easily clamped thereon by the operation of the manual levers and then lifted by the cable attached to the lifting hook with the assurance that the entire stack will remain intact, and may be lifted and transported at will.

I claim:

1. In a device for lifting a stack of brick or the like, the combination of a suspensible frame including a pair of shafts, a rotary cam on each shaft, a pair of jaws suspended from the shafts, seats against which the cam faces act and which in turn act against the jaws to force the upper ends of the jaws outwardly when said rotary cams are rotated, and means whereby the outward movement of the upper ends of the jaws causes inward movement of the lower ends to clamp the load.

2. In the device for lifting a stack of brick and the like, the combination of a pair of movable jaws provided at their lower ends with means for engaging a load to be lifted, a tie between intermediate regions of the jaws, said jaws being provided at their upper ends with eyes, a pair of shafts each occupying two eyes of opposed jaws, a pair of rotary cams on the shafts respectively, adapted to force the eyes outwardly as the cams are rotated, each cam having an inwardly projecting arm, and means connecting the two cam arms and adapted to be raisably engaged by a lift hook.

3. A combination of a pair of jaws provided at their lower ends with means for engaging the load to be lifted, a suspensible device carrying the jaws, an intermediate clamping device acting on the jaws to swing the lower ends inwardly while the upper ends are substantially stationary to effect a preliminary clamping of the load, and means on the suspensible device for spreading the upper ends of the jaws while the clamping device acts as a tie to prevent spreading of the intermediate region of the jaws, thereby tighten the clamping of the lower ends against the load, means for attaching a lifting cable, an operating connection between the spreading means and the means for attaching a lifting cable whereby the upward pull on the lifting cable may operate to spread the upper ends of the jaws, and means connected with the clamping device for rendering the spreading means idle when the clamp is idle.

4. A combination of a pair of jaws provided at their lower ends with means for engaging a load to be lifted, said jaws being provided with eyes adjacent at their upper ends, a pair of shafts occupying said eyes, rotary double-faced cams on said shafts, seats for the cams adapted to be engaged and spread thereby against the eyes to spread the upper ends of the jaws, springs on the shafts on the outer sides of the jaws normally retaining the jaws against the cam seats, said rotary cams having inwardly extending arms, lifting mechanism having links engaging the arms whereby the two arms may be turned up as a unit to operate the two cams to spread the upper ends of the jaws, and means forming a tie between intermediate-regions of the jaws to force the low-

er ends into clamping relation to the load when the upper ends are spread by the double faced cams.

5. In a device for lifting a stack of brick or the like, the combination of a pair of jaws each comprising a pair of upright jaw bars, a horizontal bar at the lower ends thereof adapted to engage the load, and a brace bar between the jaw bars adjacent the upper ends thereof, said jaw bars being each provided with an eye adjacent its upper end, a pair of transverse shafts loosely occupying an eye of the two jaws, rotary cam mechanism mounted on the respective shafts and adapted to bear against the eyes and spread the jaw bars, each cam mechanism having an inwardly projecting arm, means for attaching a lifting cable to the two cam arms, a pair of adjustable links connected respectively to the two bars of one jaw, levers pivoted to the corresponding bars from the other jaw and pivoted to said links, whereby the levers may adjust the distance between the load engaging bars, a pair of brackets carried by the two jaws, a rock shaft in said brackets, hooks on the rock shaft adapted to coact with the cam arms to hold them in idle position, and links connecting the rock shaft with the clamping levers whereby when the levers cause the jaws to spread at their ends they also lock the cam arms in idle position, whereby the device may be lifted and transported from place to place while in spread condition and thereafter when the clamps are operated to cause the lower ends of the jaws to engage the load the cam arms will be freed so that the lifting of the device may tighten the clamping.

6. The combination of a pair of jaws provided at their lower ends with means to engage opposite sides of a load to be lifted and each having eyes adjacent its upper end, a pair of shafts occupying the eyes of the opposed jaws, rotary cams on the respective shafts having inwardly extending arms, a member adapted to be attached to a lifting cable and connected to both cam arms to rotate the cams as the cable lifts the device, movable cam seats on the respective shafts between the cams and the eyes on the jaws, whereby the cams force the upper ends of the jaws outwardly as the device is lifted, and an intermediate device between the opposed jaws to cause the inner ends of the jaws to move inwardly when the upper ends move outwardly, said intermediate device comprising a link adjustable as to length and anchored to one of the jaws, the other end of the link being connected to a lever which is connected to the other jaw, whereby the lever may cause an inward movement of the lower ends of jaws while the upper ends are substantially stationary and thus give a preliminary clamping of the load.

7. The combination with suspensible mechanism of a pair of jaws depending therefrom, means connecting intermediate regions of the two jaws to draw them together to cause the lower ends to effect a clamping action against an interposed load, the connecting means between the jaws including a turnbuckle to adjust the length of the connection and including also means for lengthening the connecting means without disturbing the turnbuckle, and means for spreading the upper ends of the jaws.

8. The combination of means adapted to be suspended from a lift hook, a pair of inwardly depending jaws movably carried thereby, the lower ends of which are adapted to engage a load to be lifted, actuating means operatively associated with the lift hook abutting the upper ends

of the jaws and adapted to spread said ends outwardly, and adjustable means connecting with said jaws intermediately thereof to cause the lower ends to effect a clamping action against the load when the upper ends are spread, and means operating on said connecting means for spreading the lower ends of the jaws independently of the adjustment of the connecting means.

9. In a lifting device, the combination with a suspensible mechanism of a pair of depending inwardly movable jaws carried thereby, cams mounted in the suspensible mechanism and movable to act against the upper ends of the jaws to spread said ends outwardly, means adapted to be connected to a lifting cable for so moving the cams, a manually operable clamping device co-operating with the intermediate regions of the jaws and including an operating member to force the lower ends of said jaws inwardly to effect a preliminary clamping of an interposed load, said means acting as a tie to cause tightening of the clamping action between said lower ends and the load when the upper ends of the jaws are spread outwardly, and means coacting with the clamping means and the cam operating means for maintaining the jaws in open position and preventing the operation of said cams while the device is being lifted or lowered.

10. A combination of two pairs of jaws, the lower ends of which are adapted to contact a load to be lifted, means adapted to be suspended from a lifting cable and carrying the jaws adjacent their upper ends, said means including a pair of transverse shafts on which the jaws are slidably mounted, a pair of rotary cams on said shafts acting against seats bearing against the upper ends of the jaws, and levers on the cams adapted to be connected to the lift hook of a hoisting cable for rotating said cams when the cable lifts the device.

11. The combination with suspensible mechanism of a pair of jaws depending therefrom, means connecting the two jaws together in intermediate regions thereof, means for adjusting the length of said connecting means, means for changing the position of one end of the connecting means relative to the corresponding jaw without disturbing the lengthwise adjustment of said connecting means, and means for spreading the upper ends of the jaws.

12. The combination of a pair of longitudinal frame members spaced apart, two pairs of depending jaws, each pair located substantially in a vertical plane transversely to the longitudinal frame, a pair of movable cams between the frame members adapted to act against the upper ends of the jaws and move them outwardly, lever mechanism between the frame members adapted to be connected with a lift hook and operate the respective cams to spread the upper ends of the jaws and means acting intermediately on the jaws to cause the lower ends to move inwardly when the upper ends are spread.

13. The combination with suspensible mechanism for a pair of depending inwardly movable jaws, manually operable clamping means acting on intermediate regions of the jaws to force the lower ends inwardly while the upper ends act as an anchorage, and a pair of movable cams oper-

ated by the lifting cable and acting outwardly against the upper ends of the jaws to spread the upper ends while the manual clamping device acts as a tie between the jaws to force the lower ends inwardly, and means operated consequent upon the movement of the manual clamping means and coacting with the spreading means for holding the spreading means idle.

14. In a lifting device, the combination with a suspensible frame of a pair of depending inwardly movable jaws carried thereby, mechanism mounted on the suspensible frame and adapted to be operated by a lifting cable to spread the upper ends of the jaws, tying means connecting intermediate regions of the jaws to cause the lower ends of the jaws to move inwardly when the upper ends move outwardly, mechanism including a manually operable lever for lengthening said tying means to spread the lower ends of the jaws, locking means for the first-mentioned mechanism, and a connection between said lever and said locking means.

15. The combination of a frame adapted to be suspended by a cable, two pairs of jaws movably carried by the frame, an intermediate tie between the jaws of each pair causing the lower ends to move inwardly when the upper ends move outwardly, a double faced cam engaging inclined surfaces on the inner faces of the upper ends of the two jaws of each pair, and a pair of levers operated by the lifting cable and connected to the respective cams for moving said cams to spread the jaws.

16. The combination of a suspensible frame, two pairs of jaw-bars movably carried by the frame, intermediate ties between the jaw-bars of each pair causing the lower ends to move inwardly when the upper ends move outwardly, two double-faced cams movably mounted on the frame and each located respectively between the upper ends of the two jaw-bars of each pair and bearing against such upper ends, a pair of lever-mechanisms operating the cams, and means connecting the two lever mechanisms adapted to be operated by a lifting cable for actuating said cams to spread the upper ends of the jaw-bars.
